MEMORANDUM NOTE PAD UNIT

Addis T. Fitzgerald, Inglewood, Calif.

Application April 19, 1955, Serial No. 35,571

Term of patent 3½ years

(Cl. D74—1)

Fig. 1.

Fig. 2.

Figure 2 is another perspective view thereof as it appears with the cover raised and the pencil in writing position.

The undisclosed back of the unit is plain and unornamented. The broken line illustration of a pad and pencil in Figure 2 is for illustrative purposes only.

I claim:

The ornamental design for a memorandum note pad unit, substantially as shown and described.
